UNITED STATES PATENT OFFICE.

MANLY M. GILLAM, OF NEW YORK, N. Y., ASSIGNOR TO THE UNIVERSAL TIME COMPANY, OF SAME PLACE.

DESIGN FOR A CLOCK-DIAL.

SPECIFICATION forming part of Design No. 30,937, dated June 6, 1899.

Application filed April 13, 1899. Serial No. 712,933. Term of patent 14 years.

To all whom it may concern:

Be it known that I, MANLY M. GILLAM, a citizen of the United States, residing at New York, (Flushing,) county of Queens, in the 5 State of New York, have invented and produced a new and original Design for Clock-Dials, of which the following is a specification, reference being had to the accompanying drawing, forming a part hereof.

10 The drawing is a plan or face view of a dial for a clock or other timepiece, showing my new design.

As shown in the drawing, the leading or material feature of my design consists of the 15 dark portion A and the light portion B immediately above it in contrasting colors. These portions A and B are arranged centrally of

the dial and together form a circular colored portion, the starry portion being intended to represent night and the other portion day. 20

A perforation indicated by *a* is made in the dial for the passage of the hand-arbor.

The annular space between the ring *b* and the colored central portion is provided for the symbols indicating the hours. 25

Having described my invention, what I claim as new, and desire to secure by Letters Patent, is—

The design for a clock-dial, substantially as herein shown and described.

MANLY M. GILLAM.
